UNITED STATES PATENT OFFICE.

MORRIS I. GANS, OF NEW YORK, N. Y.

BELT BUCKLE.

Application filed March 31, 1926. Serial No. 98,809.

This invention relates to improvements in belt buckles.

The primary object of the invention resides in the construction of a belt buckle which embodies a means for preventing the shifting of the buckle and belt about the waist of the wearer, when the buckle is in clamping engagement with the free end of the belt.

Another object of the invention is to provide a swingable hook member on a belt buckle for engagement with the top button of the fly of a pair of mens' trousers, so that the buckle is held in position to conceal the button, and which also prevents the buckle from slipping above the waist band of the trousers, relieving the wearer of an uncomfortable feeling and giving to him a neat appearance.

A further object resides in a belt buckle which is simple in construction inexpensive of manufacture and strong and durable for the purpose intended.

With these and other objects in view, the invention resides in certain novel construction and combination and arrangement of parts, the essential features of which are hereinafter fully described, are particularly pointed out in the appended claim, and are illustrated in the accompanying drawing, in which:—

Figure 1 is a perspective view of my improved belt buckle looking toward the rear thereof.

Figure 2 is a view of the buckle in engagement with the top button of a pair of trousers.

Figure 3 is a vertical sectional view on the line 3—3 of Figure 2.

Referring more particularly to the drawing, the reference numeral 10 designates my improved belt buckle in its entirety, and which includes a metal frame 11 having its longitudinal edges bent back at right angle to provide spaced opposed flanges 12, 12 which define a passage through which the free end of a belt is adapted to pass. The other end of the belt is connected with the buckle by any suitable attaching means 13 disposed at one end thereof. In the present instance, I have shown that form of attaching means commonly employed for this purpose and which includes a plate 14 pivoted to the frame and which plate in turn carries a pivoted clamping lever 15. One

end of the belt is passed between the plate 14 and the lever 15, after which the lever is pressed into gripping engagement with the belt.

The buckle also embodies a clamping means 16 for detachably holding the free end of the belt and which means comprises a pair of opposed slots 17 in the flanges 12, which are arranged at an angle with respect to the longitudinal center of the flanges and within which the ends of a locking bar 18 is movable. When the locking bar is forced toward the front end of the slot with the free end of the belt passing through the buckle, the same serves to lock the end against accidental movement. This means is also old in the art and no claim is made to this particular construction, but has merely been shown in combination with a hook member 19, now to be described.

The hook member 19 is constructed of a flat piece of metal and comprises a body portion 20 from which extends oppositely disposed pintles 21 which have their bearings in openings 22 provided in the flanges 12 adjacent the entrance end of the passage defined by the flanges and the front wall of the buckle. The bill of the hook member is swingable beyond one end of the buckle, but when in normal position, the same lies within the confines of the frame as shown in Figure 2 of the drawing.

In practice, the buckle is attached to one end of the belt by the attaching means 13 in the manner also described and when applying the belt to the waist of a wearer, the same is inserted through the loops on the waist band of a pair of trousers 23. The hook member 19 is then swung outward and inserted between the overlapping portions of the fly of the trousers so that the threads which fasten the top button 24 or clasp to the trousers is received in the hook portion. The buckle is then swung back to a position to lie flat against the waist band and conceals the top button from view. The free end of the belt is then inserted through the entrance end of the passage and is pulled tight about the waist after which the clamping means 16 is operated to hold the free end in its adjusted position. It will now be seen that the hook member by reason of its engagement with the button, prevents shifting of the belt and serves to support the front of the trousers. This will

eliminate the necessity of providing loops at the front of the waist band of the trousers which sometime interfere with the connection of the free end with the buckle. The 5 buckle is always held in a front position so as to conceal the top button, thereby imparting a neat appearance to the wearer. A belt equipped with my improved belt buckle may be left relatively loose when adjusted to 10 the waist of a wearer and yet provide sufficient holding means for the trousers.

While I have described what I deem to be the most desirable embodiment of my invention, it is obvious that many of the 15 details may be varied without in any way departing from the spirit of my invention, and I therefore do not limit myself to the exact details of construction herein set forth nor to anything less than the whole of my 20 invention limited only by the appended claim.

What is claimed as new is:

A belt buckle comprising a base plate having parallel side flanges formed longitudinally of the base plate for guiding a strap, 25 a gripping plate pivoted to the flanges at one end of the base plate, an angular claw plate pivoted to the gripping plate for gripping one end of a belt, a hook plate pivoted to the flanges at the other end of the base 30 plate, said flanges being formed with elongated slots adjacent that end of the base plate in proximity to the pivotal mounting of the hook plate, a belt gripping post slideable in said slots for adjustably gripping the 35 other end of belt, said hook plate adapted to overlap said post and having an upturned hooked end for engaging with a trouser button.

In testimony whereof I have affixed my 40 signature.

MORRIS I. GANS.
